(57) **CLAIM**

The ornamental design for a filter, as shown.

DESCRIPTION

FIG. 1 is a perspective three-dimensional view of the inverted filter showing our new design.

FIG. 2 is a perspective three-dimensional view of the filter shown in an upright orientation.

FIG. 3 is a top view of the filter; and,

FIG. 4 is a side view of the filter.

1 Claim, 4 Drawing Sheets

FIG. 1

FIG. 2

FIG. 3

FIG. 4
